(57) ABSTRACT

A new *Chrysanthemum* plant named 'CIDZ0032' particularly distinguished by the red decorative-type inflorescences, strong vigorous growth with good branching, excellent flowering uniformity with an 8 week flowering response.

1 Drawing Sheet

1

Latin name of the genus and species of the plant claimed:
Chrysanthemum×morifolium.
Varietal denomination: 'CIDZ0032'.

BACKGROUND OF THE NEW PLANT

The present invention comprises a new *Chrysanthemum*, botanically known as *Chrysanthemum×morifolium*, and hereinafter referred to by the variety name 'CIDZ0032'.

'CIDZ0032' is a product of a planned breeding program. The new cultivar has red decorative-type inflorescences, strong vigorous growth with good branching, excellent flowering uniformity with an 8 week flowering response.

'CIDZ0032' originated from a hybridization made in January 1998 in a greenhouse in Salinas, Calif. The female parent was an unpatented, proprietary plant designated 'YB-6351'. 'YB-6351' has light pink spoon shaped inflorescences and a slower flowering response than 'CIDZ0032'.

The male parent of 'CIDZ0032' was a proprietary, unpatented plant identified as 'YB-6605' with bronze-red, single form, spoon-type inflorescences.

The resultant seed was sown in a shade structure in July 1998 in Fort Myers, Fla. 'CIDZ0032' was selected as one flowering plant within the progeny of the stated cross in December 1998, grown in pots under a shade structure in Fort Myers, Fla.

The first act of asexual reproduction of 'CIDZ0032' was accomplished when vegetative cuttings were propagated from the initial selection in March 1999 in a greenhouse in Fort Myers, Fla.

BRIEF SUMMARY OF INVENTION

Horticultural examination of plants grown from cuttings of the plant initiated in March 1999, and continuing thereafter, has demonstrated that the combination of characteristics as herein disclosed for 'CIDZ0032' are firmly fixed and are retained through successive generations of asexual reproduction.

'CIDZ0032' has not been observed under all possible environmental conditions. The phenotype may vary significantly with variations in environment such as temperature, light intensity, and day length.

2

A Plant Breeder's Right for this cultivar was applied for in Canada on Jul. 29, 2011, No. 11-7348. 'CIDZ0032' has not been made publicly available more than one year prior to the filing of this application.

The following traits have been repeatedly observed and are determined to be basic characteristics of the new variety. The combination of these characteristics distinguishes this *Chrysanthemum* as a new and distinct variety.

BRIEF DESCRIPTION OF THE PHOTOGRAPHS

The accompanying photographic drawings show typical flower and foliage characteristics of 'CIDZ0032' with colors being as true as possible with an illustration of this type.

The photographic drawings show in FIG. 1 a close-up of the flowers and in FIG. 2, 4 flowering plants of the new variety.

DETAILED BOTANICAL DESCRIPTION

The plant descriptions, measurements and aforementioned photographs were taken in Gilroy, Calif. in January 2012 under natural light. These plants were grown disbudded, 4 plants in a 5 inch pot under blackcloth controlled greenhouse trial conditions in Gilroy, Calif. These plants were 10-12 weeks old.

Color references are made to The Royal Horticultural Society Colour Chart (R.H.S.) 2001.

TABLE 1

DIFFERENCES BETWEEN THE NEW VARIETY 'CIDZ0032' AND A MOST SIMILAR VARIETY		
	'CIDZ0032'	'Yotobago' (U.S. Plant Pat. No. 15,412)
35 Inflorescence size:	Larger	Smaller
Inflorescence color:	Darker red	Lighter red
Flowering response time:	1 week faster	1 week slower

Plant:

Form, growth and habit.—Herbaceous pot-type, stems upright, good branching, strong and moderately vigorous growth habit with good flowering uniformity.

<i>Plant height.</i> —About 25.0 cm.		5	<i>Immature inflorescence:</i>
<i>Plant height (inflorescence included).</i> —29.0-33.0 cm.			<i>Diameter.</i> —7.0-7.5 cm.
<i>Plant width.</i> —20.0-24.0 cm.			<i>Color of ray florets, upper surface.</i> —Closest to RHS 185A but deeper more velvety.
<i>Roots:</i>			<i>Lower surface.</i> —RHS 162C with longitudinal bars of RHS 180A towards the apex and on margins.
<i>Number of days to initiate roots.</i> —About 4 days at about 22 degrees C.	5		<i>Mature inflorescence:</i>
<i>Number of days to produce a rooted cutting.</i> —About 10 days at 22 degrees C.			<i>Diameter.</i> —10.0-11.0 cm.
<i>Type.</i> —Fine, fibrous, free branching.	10		<i>Depth.</i> —3.0-3.5 cm.
<i>Color.</i> —RHS N155B but whiter.			<i>Total diameter of disc.</i> —Indistinct to date.
<i>Foliage:</i>			<i>Receptacle color.</i> —Closest to RHS 144B.
<i>Arrangement.</i> —Alternate.			<i>Receptacle height.</i> —0.5 cm.
<i>Immature, leaf color, upper surface.</i> —Closest to RHS 147A.	15		<i>Receptacle diameter.</i> —0.7 cm.
<i>Lower surface.</i> —RHS 147B but more green.			<i>Ray florets:</i>
<i>Mature, leaf color, upper surface.</i> —Closest to RHS 147A.			<i>Average quantity of florets.</i> —Approximately 225 in several whorls.
<i>Lower surface.</i> —RHS 147B but more green.	20		<i>Color of florets, upper surface.</i> —Closest to RHS 53A but deeper and a little more purple hue.
<i>Length.</i> —6.7-7.5 cm.			<i>Lower surface.</i> —RHS 162B heavily overlaid with RHS 181C to RHS 181D in a slight cross-hatched like plaid pattern.
<i>Width.</i> —4.5-5.3 cm.			<i>Length.</i> —4.1-5.1 cm.
<i>Shape.</i> —Ovate.			<i>Width.</i> —0.9-1.1 cm.
<i>Base shape.</i> —Attenuate.			<i>Shape.</i> —Elliptical.
<i>Apex shape.</i> —Mucronulate.			<i>Apex shape.</i> —Obtuse.
<i>Margin.</i> —Palmately lobed, irregularly incised and serrate.	25		<i>Base shape.</i> —Cuneate.
<i>Texture, upper surface.</i> —Bifid T-shaped hairs.			<i>Margin.</i> —Entire.
<i>Lower surface.</i> —Bifid T-shaped hairs.			<i>Texture, upper surface.</i> —Papillose.
<i>Color of veins, upper surface.</i> —RHS 147C.	30		<i>Lower surface.</i> —Papillose.
<i>Color of veins, lower surface.</i> —RHS 147C.			<i>Disc florets:</i>
<i>Pattern of veining.</i> —Palmate.			<i>Average quantity of florets.</i> —About 4-6, are very immature to date.
<i>Petiole color.</i> —RHS 147C.			<i>Color of florets.</i> —RHS 155C with about RHS 1B at apex.
<i>Length.</i> —2.2-3.0 cm.			<i>Length.</i> —0.2 cm.
<i>Diameter.</i> —0.25 cm.	35		<i>Width.</i> —0.05 cm.
<i>Texture.</i> —Bifid T-shaped hairs.			<i>Shape.</i> —Tubular, elongated.
<i>Stem:</i>			<i>Apex shape.</i> —Acute, 5 pointed.
<i>Quantity of main branches per plant.</i> —4-5.			<i>Texture, inner surface.</i> —Glabrous.
<i>Color of stem.</i> —RHS 146A but appears lighter due to hair.	40		<i>Outer surface.</i> —Glabrous.
<i>Length of stem.</i> —20.0-25.0 cm.			<i>Phyllaries:</i>
<i>Diameter.</i> —0.4-0.5 cm.			<i>Quantity.</i> —About 20 with additional bracts amongst the ray florets.
<i>Length of internodes.</i> —0.5-2.0 cm.			<i>Color, upper surface.</i> —RHS 137A but appears lighter due to hair.
<i>Texture.</i> —Bifid T-shaped hairs.			<i>Lower surface.</i> —RHS 137A.
<i>Color of peduncle.</i> —RHS 146A but appears lighter due to hair.	45		<i>Length.</i> —0.6-1.0 cm.
<i>Length of peduncle.</i> —3.0-3.5 cm.			<i>Width.</i> —0.2-0.25 cm.
<i>Peduncle diameter.</i> —0.4 cm.			<i>Shape.</i> —Lanceolate.
<i>Texture.</i> —Bifid T-shaped hairs.			<i>Apex shape.</i> —Acute.
<i>Inflorescence:</i>			<i>Base.</i> —Fused.
<i>Type.</i> —Compositae type, solitary decorative-type inflorescences, borne terminally above foliage, ray florets arranged acropetally on a capitulum.	50		<i>Margins.</i> —Entire; some papery.
<i>Quantity of short days to flowering (response time).</i> —About 8 weeks.			<i>Texture, upper surface.</i> —Glabrous.
<i>Natural season flowering.</i> —Not determined on this variety.			<i>Lower surface.</i> —Bifid T-shaped hairs.
<i>Quantity of inflorescences per plant.</i> —3-4.			<i>55 Reproductive organs:</i>
<i>Lastingness of individual blooms on the plant.</i> —About 4 weeks.	60		<i>Pistil.</i> —1, found on both types of florets.
<i>Fragrance.</i> —Slightly spicy.			<i>Length.</i> —0.3 cm.
<i>Bud (just when opening/showing color):</i>			<i>Style color.</i> —RHS 155C.
<i>Color.</i> —Between RHS 183C and RHS 183D.			<i>Style length.</i> —0.2 cm.
<i>Length.</i> —1.9-2.5 cm.			<i>Stigma color.</i> —RHS 1C.
<i>Width.</i> —1.7-2.4 cm.	65		<i>Stigma shape.</i> —Bi-parted.
<i>Shape.</i> —Broadly oblate.			<i>Ovary color.</i> —RHS 155C but a little more green.

US PP24,097 P2

5

Length filaments.—0.3-0.4 cm.

Anther color.—RHS 15C.

Anther length.—0.1 cm.

Anther shape.—Oval.

Color of pollen.—RHS 21A.

Pollen amount.—Poor.

Fertility/seed set.—Has not been observed to date.

6

Disease/pest resistance.—Has not been observed to date.

What is claimed is:

1. A new and distinct variety of *Chrysanthemum* plant
5 named 'CIDZ0032' substantially as illustrated and described
herein.
